CLAIM

The ornamental design for a scooter, as shown and described.

DESCRIPTION

FIG. 1 is a front top perspective view of a scooter in accordance with the new design;

FIG. 2 is a rear top perspective view thereof;

FIG. 3 a left side elevation view thereof;

FIG. 4 is a right side elevation view thereof

FIG. 5 is a front elevation view thereof;

FIG. 6 is a rear elevation view thereof;

FIG. 7 is a top elevation view thereof; and,

FIG. 8 is a bottom elevation view thereof.

The broken lines are for the purpose of illustrating portions of the scooter that form no part of the claimed design.
